UNITED STATES PATENT OFFICE.

GEORGE H. BLACK, OF ROCHESTER, NEW YORK, ASSIGNOR, BY MESNE ASSIGNMENTS, TO
UNITED SHOE MACHINERY CORPORATION, OF PATERSON, NEW JERSEY, A CORPOR-
ATION OF NEW JERSEY.

WELT-SHOE AND METHOD OF MAKING SAME.

1,301,084.

Specification of Letters Patent. Patented Apr. 15, 1919.

Application filed November 10, 1917. Serial No. 201,372.

To all whom it may concern:

Be it known that I, GEORGE H. BLACK, a citizen of the United States, residing at Rochester, in the county of Monroe and 5 State of New York, have invented certain Improvements in Welt-Shoes and Methods of Making Same, of which the following description, in connection with the accompanying drawings, is a specification, like 10 reference characters on the drawings indicating like parts in the several figures.

This invention relates to the manufacture of welt shoes and to a method and means for securing "close" shanks.

15 In the manufacture of welt shoes there are two conditions which tend to produce fullness in that portion of the shank of the shoe adjacent to the heel breast. One of these conditions is that this portion of the 20 shank includes more upper materials than does the forward portion of the shank because the counter or heel stiffener wings extend into this portion of the shank. The second condition is that these upper materials are fastened by the inseam to the rear 25 end portions of the insole lip or sewing rib and said end portions of the rib have greater freedom to pull or bend outwardly than do the portions of the rib farther removed from 30 its end. The two conditions work together because the extra thickness and stiffness produced by the wings of the counter render it difficult to sew this portion of the shoe as close down to the base or root of the sewing 35 rib as it is practical to sew the portions in the forward portion of the shank.

In efforts to overcome these difficulties and produce close shank shoes, which are desirable because of their more pleasing appearance and better fit, various inventions have 40 been made by which the counters have been especially shaped at this portion of the shoe; lasting machines have been equipped with special mechanism for preparing the 45 shoe for sewing at the shanks; and special machines have been devised for forcing inwardly and fastening the shoe stock at and adjacent to the ends of the inseam after the shoe was welted, so as to narrow the shank.

50 An object of this invention is to provide a method of obtaining close shanks by the practice of which the shoe upper materials may be drawn snugly about the last in the shank during the attachment of the shoe

upper materials to the insole and maintained 55 in said position. Another object of the invention is to provide an improved insole having characteristics which facilitate the practice of this method and contribute to the production of close shanks. 60

In one of its aspects the method of this invention consists in producing an insole with a sewing rib to provide an anchorage for inseam stitches in attaching a shoe upper to the insole, providing additional anchorage for the sewing rib at the rear part of the shank relatively to other portions of the sewing rib, and then sewing the shoe upper materials to the insole and utilizing said anchored portion of the rib at the rear part 70 of the shank to pull the upper materials snugly about the last and against the rib. In another of its aspects the invention consists in bending the rear end portion of the sewing rib inwardly away from the adjacent 75 edge of the insole and fastening said portion in its inwardly bent position to hold it for the operation of sewing the upper materials to the rib while it occupies said inwardly bent position. By the method of this invention the portions of material in the shank which are rendered bulky by the presence of the wings of the heel stiffener are carried farther inwardly from the edge of the insole during the sewing operation than are the 85 portions of upper material in the forward part of the shank, and by reason of the additional anchorage provided for the inseam stitches at the rear part of the shank the upper materials are secured in said inward 90 position by the inseam. The bending of the sewing rib inwardly not only locates it and the inseam of which it forms a part farther from the inward edge of the insole and holds the end of the rib from being pulled 95 outwardly, but also facilitates the sewing of the inseam close to the root or base of the rib. This reduces or eliminates the chance for the upper materials to be forced outwardly, by the outward tipping of the rib, as for example under the pressure applied to the shoe in the heel attaching operation. 100

An important feature of this invention consists in a welt shoe insole having a sewing rib the rear end portion of which is formed and arranged to provide additional anchorage for the inseam stitches relatively to other portions of the sewing rib. Another 105

feature of this invention consists in an insole having a sewing rib the rear end portion of which is bent inwardly toward the body of the insole and away from the adjacent edge 5 of the insole, and still a further feature consists in a welt shoe insole the sewing rib of which is bent inwardly away from the adjacent edge of the insole and fastened in inwardly bent position. A machine which 10 may be successfully used in the practice of the present invention is shown and described in a co-pending application Serial No. 201,371, filed by me on even date herewith. Other features of the invention including 15 certain details of construction will appear from the following description and will then be pointed out in the claims.

Figure 1 of the drawings shows an insole having a sewing rib of a usual construction. 20 Fig. 2, partly in transverse section, illustrates the step of bending the rear end portion of the sewing rib inwardly away from the adjacent edge of the insole.

Fig. 3 is a similar view showing the steps 25 of setting the sewing rib in its inwardly bent position by pressure exerted substantially perpendicular to the face of the insole, and by a blow applied in a similar direction, and further illustrates the step of fastening the 30 sewing rib in its inwardly bent and set position.

Fig. 4 is a perspective view of an insole made in accordance with this invention.

Fig. 5 shows a welted shoe made by the 35 practice of the present method and the use of the insole shown in Fig. 4.

The insole chosen for illustration is of the type known as an "Economy" insole comprising a leather body 2 reinforced by can- 40 vas 4 extending across the body of the insole and upwardly against the inner side of the leather-stock portion of the sewing rib 5.

The first step in improving this insole in accordance with the present method is to 45 engage the rear end portion of the rib and bend it inwardly away from the adjacent edge of the insole and downwardly toward the body portion of the insole. This step is illustrated in Fig. 2 as effected by thrusting 50 or wedging the insole laterally between a work table 8 and a resilient bending device 10. The inwardly and downwardly directed pressure effected in this manner while the inner face of the rib is unsupported tends to 55 displace the rib inwardly and bend the constituent parts of the rib to a position more remote from the edge of the insole than that occupied by it in Fig. 1 and farther inwardly than the portions of the rib in the 60 forward part of the shank of the insole. The effect of this is to give more room between the edge of the insole and the outer face of the sewing rib within which to dispose the upper material rendered bulky in 65 the rear portion of the shank by the presence

of the wing 12 (Fig. 5) of the heel stiffener. The position of the rear portion of the sewing rib secured by the above described action is rendered more permanent and the displacement of this portion of the rib inwardly is somewhat increased by the steps of compressing the inwardly bent portion of the rib downwardly upon the portion of the insole as shown in Fig. 3 and also by beating the inwardly bent portion of the rib as also 70 illustrated in Fig. 3. The compression is shown as effected by forcing the work table with the insole thereon upwardly and engaging the inwardly bent portion of the rib with the lower face of a compressing member 14 which may be the nozzle of the tacking machine. The beating is shown as effected by a blow from a hammer 16 shown as a tack driver operating from the nozzle. 75

The inwardly bent position of the end portion of the rib is made secure by the insertion of a tack 15 through said inwardly bent rib and into the body of the insole, the tack being inserted by the hammer 16 and preferably clenching its point on the work supporting table 8 to avoid a point projecting from the foot-engaging face of the insole. Some of the advantages of this invention 80 may be obtained by treating only one of the end portions of the sewing rib of an insole, 85 but preferably both end portions are similarly treated as illustrated in Fig. 4. 90

When the insole thus produced and illustrated in Fig. 4 is incorporated in a shoe and the upper materials including the welt fastened to the rib by the inseam the position of the end portion of the rib with relation to the edge of the insole gives increased space within which to dispose the relatively bulky upper materials overlaid and fastened at 95 this portion of the shoe, as compared with the less bulky upper materials in the forward portion of the shank, see Fig. 5, and produces what is termed a "close" shank, that is, a shank presenting no bulge at its rear part 105 caused by the extra thickness of the upper materials in that part of the shoe. 110

The inwardly forced and bent-over portion of the sewing rib at the rear end of the shank presents an undercut inner wall with 115 which the channel guide of the inseam sewing machine engages. This formation has the effect of guiding the shoe bottom and the bottom face of the channel guide into close proximity as the end portions of the inseam 120 are being sewed so that the inseaming machine is compelled to sew "low" or close to the root of the rib at the ends of the inseam. This is in marked contrast with the usual insole condition wherein the sewing rib is 125 more likely than not to be bent outward and present the most difficult condition for sewing low. By inserting a fastening in cooperative relation with the sewing rib at its rear end the sewing rib is held against out- 130

ward displacement by the strain of the upper materials and also the tack increases the anchorage offered by the sewing rib at this point. During the sewing of the shoe, that 5 is the attachment of the upper and welt, this anchored portion of the rib may be utilized to pull against thus drawing the upper materials snugly into position. By anchoring the rear end portion of the sewing rib in this 10 manner the pressure exerted on this portion of the shoe during the heeling operation, which pressure tends to force the sides of the shoe outwardly, particularly if the sewing rib is inclined outwardly, is entirely 15 avoided. The tack is not regarded as absolutely essential but experience has indicated that it contributes to the benefits derived from this invention. Obviously other fastenings than tacks might be substituted. The 20 tack 15 is preferably located immediately back of the point where the last inseam stitch should be taken and as close as practicable to that point. By reason of this location, the tack is not liable to be struck by the sewing 25 needle, thereby disturbing the tack or damaging the needle or the shoe and it serves its rib holding function with maximum efficiency when so located. Furthermore, tacks so located constitute gages or guides 30 for indicating to the sewing machine operative the points at which to begin and end the inseam, these points being advantageously located at predetermined and uniform distances from the rear end of the shoe. It 35 is considered good shoemaking practice to extend the inseam a uniform short distance back of the heel breast line or location and this invention contributes to the successful carrying out of that practice.

40 Having explained the nature of this invention and described how it may be practised, I claim as new and desire to secure by Letters Patent of the United States:—

1. That improvement in methods of obtaining close shanks in welt shoes which consists in forcing the rear part of the sewing rib of the insole inwardly relatively to the forward part of the sewing rib and away from the edge of the insole and sewing the 45 upper to said rib while maintaining the rib in that position.
2. That improvement in methods of obtaining close shanks in welt shoes which consists in bending the rear portion of the sewing rib of the insole in the shank inwardly relatively to the forward part of the sewing rib, securing the rear portion only of the rib in such inwardly bent position, and then 50 weltting the shoe.
3. That improvement in methods of obtaining close shanks in welt shoes which consists in bending the rear portion of the sewing rib of the insole inwardly away from the edge of the insole and relatively to the 55 part of the rib in the forward portion of the

shank and downwardly toward the body of the insole, inserting a fastening to hold it in the position thus secured, and sewing the upper and welt to the rib along the shank.

4. That improvement in methods of obtaining close shanks in welt shoes which consists in disposing the sewing rib along the shank portion of the insole at an appropriately greater distance from the edge of the insole in the rear part of the shank than in the forepart to allow for the additional thickness of the upper materials caused by the stiffener wings in the rear part of the shank, and sewing the upper materials to the sewing rib so disposed. 70

5. That improvement in methods of obtaining close shanks in welt shoes which consists in bending the rear portion of the sewing rib of the insole in the shank inwardly away from the edge of the insole 75 and relatively to the forward part of the sewing rib and beating said rear part of the sewing rib locally to set it in overbent position. 80

6. That improvement in methods of obtaining close shanks in welt shoes which consists in bending the rear portion of the sewing rib of the insole inwardly away from the edge of the insole and relatively to the forward part of the sewing rib and applying positioning-fixing pressure to said overbent portion in a direction substantially 90 perpendicular to the plane of the insole. 95

7. That improvement in welt shoe insoles which consists in a sewing rib located farther inwardly at the rear part of the shank than along the forepart of the shank to provide a width of feather along the shank substantially proportional to the thickness of upper in the rear part of the shank that includes the heel stiffener wings and the thickness of the upper materials in the forepart of the shank that do not include the 100 stiffener wings. 105

8. That improvement in methods of making close shank welt shoes which consists in producing an insole with a sewing rib to provide an anchorage for inseam stitches in attaching a shoe upper to the insole, providing additional anchorage for the rib at the rear part of the shank relatively to other portions of the rib, sewing a shoe upper and a welt to the insole and utilizing said anchored portion of the rib at the rear part of the shank to pull the upper and the welt 110 snugly against the insole rib, and thereafter sewing an outsole to the welt and completing its manufacture in the usual manner. 115

9. That improvement in methods of making close shank welt shoes which consists in producing an insole with a sewing rib to provide an anchorage for inseam stitches in attaching a shoe upper to the insole, applying separate means to the sewing rib at the rear part of the shank to increase 120 125 130

the anchorage offered by the sewing rib at this point, and thereafter sewing the outsole to the welt and completing its manufacture.

- 5 10. A welt shoe insole having a sewing rib to which inseam stitches are anchored in attaching a shoe upper to the insole, said sewing rib at the rear part of the shank being formed and arranged to provide additional anchorage for inseam stitches relatively to other portions of the sewing rib.
- 10 11. A welt shoe insole having a sewing rib to which inseam stitches are anchored in attaching a shoe upper to the insole and provided with means coöoperating with the said rib at the rear part of the shank to provide additional anchorage for inseam stitches relatively to other portions of the sewing rib.
- 15 12. A welt shoe insole having a marginal sewing rib folded inwardly at its rear end relatively to other portions of the sewing rib, and a fastening holding the sewing rib in said folded position for it to resist outwardly directed strain.

- 20 13. A welt shoe insole having a sewing rib upstanding around the forepart of the shoe and along the forepart of the shank, said rib being bent inwardly away from the adjacent edge of the insole and downwardly toward the body of the insole in the rear part of the shank.

- 25 14. A welt shoe insole having a sewing rib freely upstanding around the forepart of the insole and means for holding the rear

end portion of said rib in the shank against outwardly directed strain.

15. A welt shoe insole having a sewing rib formed into position tending to locate the inseam farther inwardly from the edge 40 of the insole in the rear part of the shank than in the forepart of the shank.

16. A reinforced welt shoe insole having a sewing rib including an upturned portion of the insole body and a portion of the reinforcing material, said rib being folded inwardly and secured by a fastening at its rear end in the shank.

17. A reinforced welt shoe insole having a sewing rib including an upturned portion 50 of the insole body and a portion of the reinforcing material, said rib being secured at its rear end against bending or being pulled outwardly.

18. That improvement in methods of obtaining close shanks in welt shoes which consists in forming the insole with a sewing rib upstanding around the forepart and the forward portion of the shank of the shoe and in forming the rib to present an undercut inner wall at the rear end of the shank, and in engaging the channel guide of the inseam sewing machine with said undercut inner wall to sew the upper close to the root of the rib at the rear end of the shank while 60 65 inseaming the shoe.

In testimony whereof I have signed my name to this specification.

GEORGE H. BLACK.
